DESIGN FOR A GIRDLE

Hazel Miller Colby, Chicago, Ill.

Application January 12, 1948, Serial No. 143,664

Term of patent 14 years

(Cl. D20—2)

To all whom it may concern:

Be it known that I, Hazel Miller Colby, a citizen of the United States, residing at Chicago, in the county of Cook and State of Illinois, have invented a new, original, and ornamental Design for a Girdle, of which the following is a specification, reference being had to the accompanying drawing, forming part thereof.

I claim:

The ornamental design for a girdle, substantially as shown.

HAZEL MILLER COLBY.
